UNITED STATES PATENT OFFICE.

JOHN W. BROWN, OF COLUMBUS, OHIO, ASSIGNOR TO THE JOHN W. BROWN MANUFACTURING COMPANY, OF COLUMBUS, OHIO, A CORPORATION OF OHIO.

LAMP.

1,359,322.

Specification of Letters Patent. Patented Nov. 16, 1920.

Application filed October 24, 1918. Serial No. 259,461.

To all whom it may concern:

Be it known that JOHN W. BROWN, a citizen of the United States, residing at Columbus, in the county of Franklin and State 5 of Ohio, has invented certain new and useful Improvements in Lamps, of which the following is a specification.

This invention relates to lamps and is designed particularly for use in connection 10 with automobile lamps where it is frequently necessary to remove the cover or lens ring. The structure is designed with a two-fold purpose in view, these being to guard against the accidental dislodgment of the 15 lens ring and secondly, to always maintain the reflector in its proper focal relation with the lamp body no matter how many times it is necessary to remove the lens ring. These objects I attain by the employment of 20 a shelf structure upon the lamp body which coöperates with a complementary shelf structure on the reflector together with means for drawing the lens ring into its applied position upon the lamp body. This latter operation 25 is usually accompanied by a partial rotation of the lens ring upon the lamp body and to positively guard against accidental removal of the ring, and supplemental latch structure is provided whereby, when the lens 30 ring and lamp body have reached their proper relative positions of association, the latch becomes effective to permanently hold the parts in their assembled relation.

The preferred embodiment of my invention 35 is shown in the accompanying sheet of drawings in which similar characters of reference designate corresponding parts and in which,

Figure 1 is a view partially in side elevation and partially in central section illustrating my improved structure in connection 40 with an automobile head light,

Fig. 2 is a fragmentary perspective looking from the inside of the lens ring, and 45 Fig. 3 is a fragmentary perspective of a portion of the lamp body showing one of the shelves upon which the reflector flange rests and the spring means for drawing the lens ring into proper position with the remaining 50 lamp parts.

In these drawings, the lamp body is designated by the reference numeral 1 and is illustrated with particular clearness in Fig.

3, a plurality of angular shelf elements 2 are 55 applied at proper intervals. This latter

structure comprises an upper flat main shelf 3 and a depending tongue portion 4 which forms a means for properly attaching the shelf itself to the lamp body as shown for instance at 5. This means of attachment 60 may take any desired form. It will also be noted by reference to Fig. 3 that the shelf proper 3 is located slightly beneath the upper edge 6 of the lamp body and it is upon these shelves that the coöperating flange or 65 shelf 7 carried by the reflector 8 are designed to rest. By the provision of this structure, the reflector can not vary from its properly applied position with respect to the lamp bulb although the body itself may be 70 adjusted to alter its focal arrangement by means of the structure illustrated diagrammatically at 9. The lamp body and reflector are closed by means of the lens 10 suitably mounted within the lens ring 11. This lens 75 ring is provided with a plurality of slots 12 located in the flat portion or complementary shelf portion 13 which is designed to rest upon the flange 7 of the reflector as shown in Fig. 1. The surfaces defining and immediately surrounding these slots are perfectly flat as is illustrated and it is through these slots that the spring hooks 14 are designed to pass. It will be noted by reference to 80 Figs. 1 and 3 that these spring hooks are 85 each formed of a single piece of wire provided with reverse bends 15 and 16, the latter projecting through the shelf 3 as shown at 17 and carrying an engaging portion 18 at its extreme end. Each of these wire 90 hooks is secured at its opposite end to the shelf 3 by any suitable means as, for instance, the bolt and nut structures shown at 18. The reflector flange is suitably cut out to accommodate or to permit the passage 95 therethrough of wire hooks 14 and these hooks then engage the lens ring by passage through the slots 12 and a partial rotation of the lens ring in its applied position upon the lamp. The hooks 14 are preferably 100 made of spring wire in order to at all times exert a tension upon the lens ring urging it into firm holding relation with the remaining lamp parts to avoid rattle.

In order to prevent the accidental dislodgment of the lens ring after it has been properly applied, I have provided an auxiliary latch which takes the part of a spring wire 105 19 suitably secured at one end as shown at 20 to the lamp body and having a substan- 110

tially right angular bend 21 at its opposite end. The lamp body is provided at this point with an aperture or slot 22 and the lens ring is itself provided with a slot 23, these slots being designed to align when the parts are in their properly associated position to permit the end 21 of the auxiliary latch to assume the position shown in Fig. 1. It will thus be apparent that the parts are firmly locked against accidental removal. However, to permit manual removal of the lens ring I have provided the auxiliary latch 19 with a push button 24 which passes through the lamp body as shown in Fig. 1 and is preferably located on the under side of the lamp body. Should it be desired to remove the lens ring, all that is necessary is to force the auxiliary latch inwardly by pressure on the button 24 and then partially rotating the lens ring. Similarly, this auxiliary latch must be slightly retracted when the lens ring is applied.

What I claim is:

1. In a headlight, a lamp body, a reflector therein, a laterally projecting shelf structure carried by said reflector, a plurality of coöperating shelves of angular form secured to said body and formed of an upper flat portion arranged circumferentially within said body and beneath its top edge said flat portion terminating in a depending tongue, a spring wire secured at one end to the underside of the flat portion of each shelf and provided with a pair of reverse bends, said wires projecting through their shelves for

coöperation with said ring, and means carried by said ring for coöperating with said spring wires.

2. In a headlight, a lamp body having an open end, a plurality of shelf elements securely mounted upon the peripheral portion of said body, said elements including angularly bent flanges disposed to occupy a plane substantially perpendicular to the longitudinal axis of the body, a reflector arranged to be mounted within said body for coöperation with a source of light therein, a slotted flange formed circumferentially upon said reflector and arranged for seating coöperation with said element flanges, a lens carrying ring removably fitted upon the open end of said lamp body, said ring including a slotted reflector engaging shelf portion, and a plurality of resilient hook members of spring wire formation secured to the inner sides of said shelf elements, each member including a pair of reverse bends, the intermediate portions of which being arranged to project through registering openings formed in the flanges of said shelf elements, the slots of said reflector flange and the slots of the shelf portion of said lens ring, whereby the bends formed upon the free ends of said hook members will be brought into engagement with the shelf portion of said lens ring to draw the latter inwardly into clamped relationship with said reflector and body.

In testimony whereof I affix my signature.
JOHN W. BROWN.
